UNITED STATES PATENT OFFICE

WILLIAM C. DUNN, OF CHICAGO, ILLINOIS

SLIDE-VALVE MOTOR

Application filed August 25, 1927. Serial No. 215,327.

This invention relates to improvements in slide valve motors, and has for its object improved means for sealing the valves around and adjacent the ports.

5 A further object of the invention is to improve the construction of the motor in such a manner that the slide valves may be readily removed through the top of the motor, thereby rendering it easy to remove the 10 valves when desired.

To the attainment of these ends and the accomplishment of other new and useful objects as will appear, the invention consists in the features of novelty in substantially 15 the construction, combination and arrangement of the several parts hereinafter more fully described and claimed and shown in the accompanying drawings illustrating this invention, and in which—

20 Figure 1 is a vertical longitudinal sectional view of an engine constructed in accordance with the principles of this invention.

Figure 2 is a detail horizontal sectional view taken on line 2—2, Figure 4.

25 Figure 3 is a detail horizontal sectional view taken on line 3—3, Figure 5.

Figure 4 is a sectional view taken on line 4—4, Figure 2.

Figure 5 is an elevation taken on line 5—5, 30 Figure 3, with parts broken away.

Figure 6 is an enlarged detail and fragmentary view of the lubrication grooves shown in Figure 4.

35 Figure 7 is a detail horizontal sectional view showing the outer cylinder and the valves with the inner cylinder and piston removed.

Figure 8 is a view similar to Figure 7, 40 showing the manner of adjustment of the valves so that they may be removed through the top of the outer cylinder.

Figure 9 is a view of Figure 8.

Figure 10 is a detail view taken on line 45 10—10, Figure 5, with parts removed.

Figure 11 is a front elevation of Figure 12.

Figure 12 is a side elevation of Figure 11.

Referring more particularly to the drawings the numeral 15 designates a casing at

the upper end of which is supported an outer cylinder 16.

Within the casing 15 and beneath the cylinder 16 is a base member 17 upon which is supported an inner cylinder 18. The 55 lower end of the inner cylinder is reduced as at 19 to form a circumferential shoulder 20, the reduced portion 19 projecting into an opening in the base 17, and encompassing the reduced portion of the cylinder and within 60 the base 17 is a space 21 for a cooling medium such as water or the like.

The cylinder above the base 17 is provided with a space 22 extending thereabout and a communicating passage 23 is provided 65 between the spaces 21 and 22 for the circulation of the fluid, a packing 24 being provided to form a fluid tight joint.

The inner cylinder is provided with a closed end 25 having an open recess 26 there- 70 in and a head 27 is provided for the inner and outer cylinder. The head is provided with lugs or projections 28 which co-operate with lugs or projections 29 on the outer cylinder, and fastening bolts 30 pass through 75 lugs 28 and 29 for securing the head 27 in position.

The head 27 is provided with a downwardly opening recess 31 which co-operates with the recess 26 to form a space for cooling fluid 80 and packing 32 may be provided between the end of the cylinder and the head to form a fluid tight joint.

The head 27 is provided with a recess 33 in which a spark plug 34 is located and the 85 plug is seated in an opening in the head 25 of the inner cylinder.

The inner and outer cylinders are arranged in spaced relation and registering intake ports 35—36 and registering outlet ports 90 37—38 are arranged in the cylinders.

The head 27 is provided with a space 39 therein which communicates with the space between the inner and outer cylinder, and the space 39 in the head is preferably slightly 95 greater in size than the space between the cylinders.

Reciprocable within the space between the cylinders and encompassing the inner cylinder are two semi-cylindrical valves 40 and 100

41 which are provided respectively with ports 42—43 therein adapted to be brought into register with the respective intake and outlet ports.

5 The semi-cylindrical valves extend about the inner cylinder and the proximate adjacent edges terminate for a considerable distance short of each other for a purpose to be hereinafter set forth.

10 Each of the valves 40 and 41 is provided with an enlarged portion 44 on the outer face of their lower ends, having a dove-tailed recess 45 for the reception of a plug 46, which latter is held in position by means of a fastening screw 47. Spaced eyes 48 are provided on the plug by means of which one end of a link 49 is pivotally connected as at 50. The other end of the link is pivotally connected as at 51 to a crank 52 which is rotatable in the usual manner. The link 44 is of such a length that the valves 40 and 41 will open and close on both the up and down stroke and the valves 40 and 41 are so arranged that they will work in opposition to each other. That is when one of the valves is moving in one direction the other valve will move in the opposite direction.

15 Within the inner cylinder 18 is a piston 53 which is connected by means of a link 54 with a crank shaft 55.

20 Encompassing the intake and the exhaust ports of the inner cylinder and on the outer face of the inner cylinder are grooves 56 for the reception of oil, and extend completely about the ports to form a sealing for compression.

25 Additional oil grooves 57—58 are arranged on the outer face of the inner cylinder preferably to encompass and are spaced from the oil grooves 56.

30 Arranged in the inner face of the outer cylinder and preferably adjacent the oil grooves 56 are additional oil grooves 58, which encompass and extend about the respective intake and exhaust ports. Additional oil grooves 59 are arranged in the inner face of the outer cylinder 16, encompassing the ports therein and extending about the oil grooves 58 so that the force of explosion in the inner cylinder when directed against the slide valves will force the valves against the inner face of the outer cylinder and the oil grooves in the cylinder face being filled with oil will form a cushion for the slide valves, while the oil grooves on the outer face of the inner cylinder will seal the space between the piston and the cylinder against escape of compression.

35 The valve members are provided with oil grooves 60 on their inner faces spaced from the ports or passages 42 therein and extending in directions transverse to the length of the slide valve.

40 Similar grooves 61 are provided on the outer faces of the piston members and are

spaced from the ports therein and extend in directions transverse to the length of the valve.

45 The grooves 61 in the piston members serve to receive the oil or lubricant from the space between the inner and outer cylinders and draw the same in a film downwardly when the slide valves are lowered, so that the grooves 60 and 61 will be filled with lubricant. These grooves also serve as a means to supply the lubricant to the other oil grooves and all of the oil grooves in the outer face of the piston and the inner face of the outer cylinder being filled with liquid, will form a cushion, while the grooves on the outer face of the inner cylinder and the inner face of the piston members will seal the space against the escape of compression.

50 The inner cylinder 18 is not fastened to any support but is supported by the shoulder 20 resting upon the base 17. The head 27 contacts with the inner cylinder and also with the outer cylinder and by drawing the head 27 against the outer cylinder by the fastening bolts 30 it will be noted that the inner cylinder will be fastened against removal and in position.

55 By removing the head 27 and then removing the inner cylinder, the slide valves after they are detached from the links 49, openings 95 in the base and closures 62 being provided for the latter purpose, may be moved one toward the other as indicated in Figure 8, so that the slide valves may be removed through the top of the cylinder.

60 Lubricant is supplied to the space 39 within the head 27 by means of suitable pipes 63, and these pipes are supplied with lubricant by means of a pipe 64 which has communication with any suitable source of supply of lubricant, the lubricant being forced through the pipe 64 and up into the pipe 63 in any desired or suitable manner.

65 While the preferred form of the invention has been herein shown and described, it is to be understood that various changes may be made in the details of construction and in the combination and arrangement of the several parts, within the scope of the claims, without departing from the spirit of this invention.

70 What is claimed as new is:—

75 1. An internal combustion engine embodying an inner and an outer cylinder arranged in spaced relation and having registering intake and exhaust ports therethrough, a removable head for the outer cylinder, said inner cylinder being removable through said open end of the outer cylinder, semi-cylindrical valves arranged within said space between the cylinders and extending in directions about the inner cylinder, and means for reciprocating the valves, the proximate longitudinal edges of the valves terminating a considerable distance short of 130

each other whereby when the inner cylinder is removed from the outer cylinder and the valves detached from their respective operating means, said valves may be bodily and laterally moved relatively one toward the other to permit their removal through the end of the outer cylinder.

2. An internal combustion engine embodying an outer cylinder open at its top, an inner cylinder removably supported within the outer cylinder, a support upon which the inner cylinder rests, a head for the open end of the outer cylinder, means for removably securing the head in position, said head co-operating with the said support for clamping and securing the inner cylinder in position, a portion of the inner cylinder telescoping into the said support, and spaced semi-circular valves encompassing the inner cylinder and disposed between the cylinders, the inner cylinder being removable through the open end of the outer cylinder, said valves when detached from their operating means being movable toward each other and removable separately through the end of the cylinder.

In testimony whereof I have signed my name to this specification on this 20th day of August, A. D. 1927.

WILLIAM C. DUNN.
